PAWL AND RATCHET MECHANISM

Graham S. McCloy, Springfield, Mass., assignor
to Westinghouse Electric Corporation, East
Pittsburgh, Pa., a corporation of Pennsylvania

Original application February 11, 1950, Serial No.
143,788, now Patent No. 2,595,967, dated May
6, 1952. Divided and this application Septem-
ber 10, 1951, Serial No. 245,907

3 Claims. (Cl. 74—128)

1

This invention relates to pawl and ratchet mechanisms and is a division of my copending application, Serial No. 143,788, filed February 11, 1950, now Patent #2,595,967 for an improvement in refrigeration apparatus.

The invention more particularly relates to improved ratchet and pawl mechanisms for counting devices such as might be used in an automatic defrosting control for refrigerators, which control initiates defrosting after the refrigerator door has been opened and closed a predetermined number of times. Controls of this type may employ a ratchet wheel which is advanced by the opening and closing of the refrigerator door. When this wheel completes one revolution it engages and moves a control member into position to energize the defrosting apparatus.

It is an object of the invention to provide novel means for actuating a ratchet wheel.

It is another object of the invention to provide a novel pawl arrangement for converting reciprocating motion of a plunger into rotary movement of a ratchet wheel.

These and other objects are effected by my invention as will be apparent from the following description and claims taken in connection with the accompanying drawings, forming a part of this application, in which:

Fig. 1 is a view of a control mechanism having the cover thereof removed and including a pawl and ratchet mechanism constructed and arranged in accordance with the invention;

Fig. 2 is a sectional view of the control mechanism shown in Fig. 1 and is taken along the line II—II of Fig. 1; and

Fig. 3 is a slightly enlarged view in perspective of the movable pawl and dog of the mechanism shown in Figs. 1 and 2.

Referring to the drawings wherein I have shown my invention as applied to a switch-actuating mechanism such as might be employed for energizing the defrosting apparatus of a domestic refrigerator, the numeral 16 designates a plunger having a rectangular portion 17 which projects into a housing 18 and slides in a rectangular groove 20 therein. When used as a defrost control the casing 18 may be so positioned within the refrigerator cabinet that the plunger is moved inwardly of the casing (upwardly as viewed in Figs. 1 and 2) each time the refrigerator door is closed. When the door is again opened, a spring 50 positioned within the casing 18 moves the plunger 16 outwardly.

A toothed ratchet wheel 22 is journaled on a fixed portion 24 (best shown in Fig. 2) of the

2

housing 18. A U-shaped spring element 26, cut from flat sheet material, is secured to the housing 18 by means of a screw 28. One leg 30 of the spring element 26 overlies the ratchet wheel 22 to retain the latter on the portion 24 of the housing 18. The other leg 32 overlies the ratchet wheel 22 and is preferably spaced axially from the end of a pin 34 in the position of the apparatus shown in Fig. 2. The pin 34 is slidably supported for axial movement within the fixed portion 24 of the housing 18.

A spring 35, formed of sheet material and best shown in Figs. 1 and 3, comprises a generally L-shaped actuating pawl 36. One leg 38 of this pawl 36 is suitably secured at its lower end to the housing 18. The upper end of the leg 38 includes a portion 39 which is bowed to the right as viewed in Fig. 1. The other leg 40 of the L-shaped actuating pawl 36 extends horizontally to the left. The free end of the leg 40 is notched at 42 and rides on the ratchet wheel 22 to engage a tooth on the periphery thereof.

The sliding element or plunger 16 has a depression 44 including an inclined face 46 formed in the portion 17 thereof. The bowed-out portion 39 of the actuating pawl 36 is biased by the leg 38 into the depression 44, and as the plunger 16 is moved upwardly, as seen in Figs. 1 and 2, the inclined face 46 engages the bowed-out portion 39 of the actuating pawl 36 and moves it together with the leg 40 to the left as viewed in Fig. 1. This leftward movement of the leg 40 advances the ratchet wheel 22 in a counterclockwise direction. The spring 35 also comprises a dog 48, which also engages a tooth of the ratchet wheel 22 and prevents clockwise rotation thereof.

When the force acting on plunger 16 is removed, the plunger moves downwardly as viewed in Fig. 2 under the action of spring 50 so that the bowed-cut portion 39 of the actuating pawl 36 together with the leg 40 moves to the right and into the depression 44. The leg 40 is resilient so that the free end of the leg 40 rides over one or more teeth of the ratchet wheel 22 to engage an adjacent tooth.

It will be observed that the bowed portion 39 of the actuating pawl 36 forms a follower for the cam surface 46 of the plunger 16. It is biased against the cam surface 46 by the leg 38 which is relatively straight to afford stiffness against vertical movement of the bowed portion 39 as viewed in Fig. 1. The leg 40 lies substantially tangentially to the ratchet wheel 22 to afford stiffness to insure transmission of the movement of the bowed portion 39 to the teeth of the ratchet wheel

22. The tangential position of the leg 40 also affords resilience to the movement of the free end of the leg 40 radially of the wheel 22 which movement allows the free end of the leg 40 to ride over the teeth of the ratchet wheel 22.

The ratchet wheel 22 carries an arcuate wedging cam 52 which is gradually forced under the leg 32 of the spring element 26 as the wheel 22 revolves and flexes the leg 32 away from the sliding pin 34. Upon further movement of the ratchet wheel 22 in the counterclockwise direction, the cam 52 releases the leg 32 which, due to its resiliency, swings back to its illustrated position and then, because of its inertia, swings beyond this position to drive the pin 34 to the left. The leg 32, being resilient, thereafter returns to its illustrated position.

A snap-acting switch element 54 is secured at its lower end in the casing 18 by a bolt 56. The element 54 comprises a switch blade 58 formed of flat spring material. The blade 58 has an inverted U-shaped slot 60 defining an upwardly extending tongue 62 in the center of the blade 58. A C-shaped compression spring 64 is interposed between the top of the tongue 62 and the upper edge of the slot 60. The spring 64 biases the upper portion of the blade 58 away from the upper portion of the tongue 62.

Two double-faced contact buttons 66 are affixed to the upper end of the switch blade 58. Two sets of contact fingers 68 and 70 are secured in the upper portion of the casing 18 by bolts 72 and 74, respectively, which bolts also form binding posts for electric conductors. The contact fingers 68 and 70 are so disposed that when the switch blade is in the left-hand position as viewed in Fig. 2, the two contact fingers 70 are bridged and when the switch blade 58 is in the right-hand position, the two contact fingers 68 are bridged. Also, if the tongue 62 is moved to the left-hand position, as viewed in Fig. 2, the switch blade 58 snaps to the right-hand position and if the tongue 62 is then moved to the right-hand position, the switch blade 58 will snap to the left-hand position.

The tongue 62 is positioned adjacent the pin 34 so that when the latter is struck by the leg 32 of the spring element 26 and the tongue 62 is in the right-hand position, it will be moved to the left-hand position under the impact of the pin 34. The bridging of the contacts 68 which results, may be used to energize suitable apparatus to effect defrosting of a refrigerator.

When the defrosting of the refrigerator is complete, the switch blade 58 must again be moved to its left-hand position or the position illustrated in the drawing, wherein normal operation of the refrigerating apparatus is effected. For this purpose a second pin 78 is positioned to the left of the tongue 62. The pin is moved to the right, as viewed in Fig. 3, by a flexible metal bellows 82 which forms one wall of the vessel 82. The vessel 82 communicates with a tube 84 and is preferably filled with a volatile fluid whose pressure varies with the temperature of the refrigerating apparatus. The movement of the pin 78 is opposed by a spring 86, one end of which engages the head 88 of the pin 78 and the other end of which engages the plate 90, the position of which may be adjusted by a screw 92. It will be understood that when the pressure of the volatile fluid acting on the bellows is increased to a predetermined value at which complete defrosting of the refrigerator is carried out, the pin 78 will be moved to the right sufficiently to force the tongue 62 to 75 ratchet wheel.

4
5 the position illustrated in Fig. 2. Accordingly, the contacts 68 are moved out of engagement with the fixed contact 68 and into engagement with the fixed contact 10 for again initiating the refrigerating cycle.

From the foregoing it will be apparent that I have provided a novel ratchet and pawl mechanism capable of transforming reciprocating motion into rotary motion. It is to be understood that I have shown and described my invention as applied to a door-operated, refrigerator defrosting control merely for the purpose of illustrating a preferred embodiment thereof and that the invention can be embodied in apparatus other than that shown and described. For example, the particular switch-actuating mechanism shown forms no part of the present invention, but is claimed in my copending application referred to above and of which the present invention is a division. Hence, the ratchet wheel 22 might be employed to actuate a rotary switch directly rather than the mechanism shown. Furthermore, the plunger 16 might be actuated by the movement of any element or machine when it is desired to count the operations of such element or machine. In such an application the ratchet wheel 22 could likewise be connected to an indicator for the purpose of indicating the number of operations of the element or machine.

While I have shown my invention in but one form, it will be obvious to those skilled in the art that it is not so limited, but is susceptible of various changes and modifications without departing from the spirit thereof.

What I claim is:

1. The combination with a toothed ratchet wheel, of a pawl for actuating said wheel, said pawl comprising a generally L-shaped spring member having first and second legs, said first leg being stationarily secured at the extremity thereof, the free end of said second leg engaging a tooth on said ratchet wheel, said second leg lying substantially tangentially to said ratchet wheel at the location of said tooth, said spring member further comprising a holding dog secured at one end to the stationary end of said first leg, the free end of said dog engaging a second tooth on said ratchet wheel, and means engaging said pawl at substantially the junction of said first and second legs for moving said second leg in said tangential direction to advance said ratchet wheel, said holding dog preventing reverse movement of said ratchet wheel when said actuating pawl is released to ride back over and engage another tooth of the ratchet wheel.

2. The combination with a toothed ratchet wheel of a unitary pawl and dog structure for actuating said wheel, said structure comprising a generally L-shaped spring member having first and second legs, said first leg being stationarily secured at the extremity thereof, the free end of said second leg engaging a tooth on said ratchet wheel, said second leg lying substantially tangentially to said ratchet wheel at the location of said tooth, said first leg of said spring member having a portion thereof struck out to form a dog for engaging a second tooth on said ratchet wheel, and means engaging said spring member at substantially the junction of said first and second legs for moving the second leg in said tangential direction to advance said ratchet wheel, said dog preventing reverse movement of said ratchet wheel when said second leg is released to ride back over and engage another tooth of the ratchet wheel.

3. A pawl and ratchet mechanism comprising a toothed ratchet wheel, a unitary pawl and dog structure for actuating said wheel, said structure comprising a generally L-shaped spring member having first and second legs, said first leg being stationarily secured at the extremity thereof, the free end of said second leg engaging a tooth on said ratchet wheel, said second leg lying substantially tangentially to said ratchet wheel at the location of said tooth, said spring member further comprising a holding dog positioned near the stationary end of said first leg, the free end of said dog engaging a second tooth on said ratchet wheel, and an actuating member arranged for reciprocating movement along a line substantially parallel to the first leg of said L-shaped member, said actuating member having a cam surface adapted to engage said L-shaped member

5
10

at substantially the junction of said first and second legs to move said second leg in said tangential direction to advance said ratchet wheel when said actuating member is moved in one direction, said holding dog preventing reverse movement of said ratchet wheel when said actuating member is moved in the opposite direction to permit said second leg to ride back over and engage another tooth of the ratchet wheel.
